TACK REMOVER

Herbert S. Holland, Orange, Conn.

Application September 12, 1934, Serial No. 743,659

4 Claims. (Cl. 254—25)

My invention relates to an improved tack remover.

My invention is of particular advantage in the association of my improved tack remover with a set of tacks, the whole being mounted on a board of suitable material for sale display and storage purposes.

The improved tack remover comprised in my invention is preferably formed of stamped metal or other suitable material, a primary structural feature of which resides in concavely formed portions of the material adjacent the head serving to reinforce the connection of the head with the handle, certain of said concavely formed portions serving as a fulcrum in the operation of removing a tack.

Preferably, the tack remover is of greatly reduced dimensions, for the essential purpose of its assembly upon and in association with a set of tacks, such as celluloid headed tacks, mounted on a board, usually rectangular, the board being of minimum dimension. The tacks are preferably arranged artistically at uniform spaces from one another and with relation to the outline of the board, the artistic effect being further enhanced by locating the tack remover substantially at the center or in other symmetrical relation relative to the tacks.

Further features and objects of the invention will be more fully understood from the following detail description and the accompanying drawing, in which

Fig. 1 is a plan view of a preferred form of assembly embodying my invention.

Fig. 2 is a sectional elevation on line 2—2 of Fig. 1, viewed in the direction of the indicated arrows.

Fig. 3 is a perspective view of my improved tack remover at a stage of removal of a tack.

Fig. 4 is a detail sectional view on line 4—4 of Fig. 3 in the direction of the indicated arrows.

Referring to the drawing, my improved tack remover, designated generally 10, has the general simulation of a miniature spoon; however, any other suitable configuration may be employed.

For the purpose of economy of material and particularly for strength yielding qualities, the tack remover as an entirety is preferably formed of sheet metal.

Essentially, the tack removed 10 comprises a head 11 of general flat configuration; the head is provided with a slot 12, preferably inwardly convergently tapered, the slot affording the head 11 to be positioned under the head 13 of a tack

and about its stem 14. Integral with such head formation 11 is the handle portion 15, terminating at its end 16 in any suitable configuration, adapted to facilitate manual grasping. Preferably, the terminal formation 16 extends downwardly relative to the body 15 of the handle, and the handle 15 inclusive of its terminal portion 16 is concavely formed. Such formation of the handle inclusive of its terminal portion 16 affords the simulation of substantiality to the handle, in that its hollow construction is concealed, the concave configuration serving further to impart sufficient rigidity to fulfill the requirements of the tool.

Further rigidity is had by the downwardly concave formation of the oppositely disposed portions 17, 18 connecting the handle 15 with the head 11.

My tack remover embodies the further distinctive structural feature of the oppositely disposed portions 19, 20, substantially at the location of connection of the stated portions 17, 18 with the handle, and extending laterally of the handle, said oppositely extending portions 19, 20, see particularly Figs. 3 and 4, being downwardly concave on their respective opposite sides of a median ridge designated 19a of the projecting portion 19 and similarly with respect to the median ridge 20a of the portion 20.

Such oppositely projecting portions 19, 20, 30 serve also as a fulcrum during the stage of removal of a tack, as appears from Fig. 3, the pressure applied manually upon the handle terminal 16 being transmitted through the body 15 of the handle, thence through the respective terminal 35 portions 19, 20, and thence through the head connecting portions 17, 18, to the head proper 11.

Desirably, the edge at the front portions indicated at 11a, 11a, of the head 11, immediately adjacent the opening of the notch 12 are convergently tapered toward the front, to facilitate entry of the stated portions under the head of a tack.

My tack remover is applicable for use not only for facilitating the removal of tacks 13 from a display board 21 but also for removal of such tacks from any location, and generally for the removal of all types of tacks.

The board 21 for the display of tacks and my improved tack remover may be of any suitable material, advantageously of paper stock which may be faced with an artistic finish material. The tack remover may be removably secured to such board by means of a staple 22 or equivalent.

My improved tack remover is readily formed

from sheet metal by blanking and forming. The faces of the metal may be coated with nickel or otherwise treated to be immune to atmospheric effects.

5 5 I claim.

1. A tack remover formed wholly of integral sheet material, comprising a head portion provided with a slot, a handle portion, and an intermediate portion integrally connecting the handle portion to the head, said intermediate portion being concavely formed, said intermediate portion including a fulcrum comprising opposingly projecting portions extending laterally thereof and integrally connected therewith.

10 15 2. A tack remover formed wholly of integral sheet material, comprising a head portion provided with a slot, a handle portion, and an intermediate portion integrally connecting the handle portion to the head, said intermediate portion including a fulcrum comprising portions extending laterally on opposing sides thereof and integrally connected therewith, said laterally extending portions being of concave formation.

20 3. A tack remover formed wholly of integral

sheet material, comprising a head portion provided with a slot, a handle portion, and an intermediate portion integrally connecting the handle portion to the head, said intermediate portion including a fulcrum comprising portions 5 extending laterally on opposing sides thereof and integrally connected therewith, said laterally extending portions being of concave formation, said handle portion and said intermediate portion being of concave formation.

10 15 4. A tack remover formed wholly of integral sheet material, comprising a head portion provided with a slot, a handle portion, and an intermediate portion integrally connecting the handle portion to the head, said intermediate portion being concavely formed, said intermediate portion including concavely formed portions extending longitudinally of the handle and merging integrally with the head, said intermediate portion including a fulcrum comprising con- 20 cavely formed laterally extending portions and integrally connected therewith.

HERBERT S. HOLLAND.
